(57) **CLAIM**

The ornamental design for a photoelectric switch, as shown and described.

DESCRIPTION

FIG. 1 is a front view showing our new design for a photoelectric switch;

FIG. 2 is a rear view of the photoelectric switch of FIG. 1; FIG. 3 is a plan view of the photoelectric switch of FIG. 1; FIG. 4 is a bottom view of the photoelectric switch of FIG. 1;

FIG. 5 is a right side view of the photoelectric switch of FIG. 1;

FIG. 6 is a left side view of the photoelectric switch of FIG. 1;

FIG. 7 is an enlarged perspective view of the claimed portion of the photoelectric switch of FIG. 1;

FIG. 8 is an enlarged plan view of the portion of the photoelectric switch in the box labeled 8 of FIG. 3;

FIG. 9 is an enlarged front view of the photoelectric switch of FIG. 1 with the cover closed;

FIG. 10 is an enlarged plan view of the photoelectric switch of FIG. 1 with the cover closed;

FIG. 11 is an enlarged bottom view of the photoelectric switch of FIG. 1 with the cover closed;

FIG. 12 is an enlarged right side view of the photoelectric switch of FIG. 1 with the cover closed; and,

FIG. 13 is an enlarged left side view of the photoelectric switch of FIG. 1 with the cover closed.

The broken lines represent environmental structure which is not a part of the claimed design.
